UNITED STATES PATENT OFFICE

PERLEY H. FULLER, OF AUBURN, MAINE, ASSIGNOR, BY MESNE ASSIGNMENTS, TO
ALEMITE CORPORATION, OF CHICAGO, ILLINOIS, A CORPORATION OF DELAWARE

LUBRICANT-EXPELLING CUP

Application filed November 10, 1925. Serial No. 68,180.

This invention aims to provide improvements in lubricant-expelling cups.

In the drawings, which illustrate a preferred embodiment of my invention:

5 Figure 1 is a plan view of a lubricant-expelling cup;

Fig. 2 is a section on the line 2—2 of Fig. 1, showing the relation of parts when the cup is filled with lubricant; and

10 Fig. 3 is a section on the same line as Fig. 2, being partly in elevation and showing the relation of parts when the cup is nearly empty.

15 Referring to the drawings, I have illustrated a lubricant cup which is adapted to feed lubricant to a part to be lubricated at a uniform rate throughout the entire period that is required to use the contents of a cup. It does not feed lubricant faster at the beginning of the stroke of the piston than at the end, as do other well known devices used for the same purposes, and therefore is much more efficient.

20 The reservoir, piston and means for filling the reservoir may be constructed in any suitable or well known manner, but I prefer to provide a reservoir 1, which has a removable cap 2, at the top, through which the stem 3 of the piston 4 may slide when the piston reciprocates in the reservoir. The stem 3 has a lubricant-receiving nipple 3^a connected to its upper end for cooperative engagement with a nozzle of a source of lubricant under pressure (not shown). A passage 5 is provided 25 in the stem to permit the lubricant to pass to the lower side of the piston. A helical coil spring 6 is interposed between the piston 4 and the cap 2 as shown in Fig. 3.

30 At the lower end of the cup, I have provided a bore 7, in which are arranged the parts which make up the automatic lubricant flow regulating means, as shown in Figs. 2 and 3. These parts include a slide valve 8, which fits into the large part of the bore 7, 35 a stop 9 threaded into the large portion of the bore and a spring 10 located in the smaller portion of the bore. The spring 10 bears against one end of the slide valve 8 and is held in the small portion of the bore by a plug 11. The slide valve has an annular

groove 12 for communication with the opening 13 above the valve and the discharge passage 14 located below the valve. A port 15 between the large portion of the bore 7 and the reservoir 1 is provided for purposes more fully hereinafter described, and a vent 16 opens the smaller portion of the bore to the atmosphere.

35 Operation of the cup is as follows:—First, assuming that the reservoir is empty, a supply of lubricant under pressure is connected to the nipple 3^a and the lubricant flows through the passage 5 to the reservoir 1 thereby forcing the piston 4 toward the top to fill the reservoir and compress the spring 6 as shown in Fig. 2. The supply of lubricant is then disconnected from the nipple 3^a and the cup is ready to feed lubricant to a part (not shown) to be lubricated. From this point on, the moving parts of the cup function automatically to feed a uniform quantity of lubricant to the part to be lubricated. When the reservoir is full of lubricant, the spring 6 exerts greater pressure on the piston 4 than it does when the reservoir is empty and between these two points the pressure exerted by the spring gradually decreases. Therefore, if the slide valve means were omitted, a gradually decreasing flow of lubricant would pass through the passage 14 to the part to be lubricated. However, the groove 12 of the slide valve cooperates with the passages 13 and 14 to automatically increase the cross-sectional area through which the lubricant passes as the pressure on the lubricant decreases. This operation will be readily understood by a comparison between Figs. 2 and 3. In Fig. 2, the pressure on the lubricant is greatest and as the lubricant passes through the port 15 and acts upon the slide valve to move it toward the shoulder 17, which provides a stop, the effective cross-sectional area through which lubricant may pass is relatively small compared with that shown in Fig. 3, when the pressure on the lubricant is greatly reduced. Therefore, in order to compensate for the decrease in pressure in the reservoir, the cross-sectional area of the passage from the reservoir to the out-

40 45 50 55 60 65 70 75 80 85 90 95 100

let 14 must be gradually increased to permit passage of the lubricant.

The shoulder 17 is important because it prevents the slide valve 8 from moving into a position which would interiorly cut off passage of lubricant from the passage 13 to the passage 14. If the passage of lubricant were cut off, the pressure of the lubricant would act upon the valve 8 and keep it closed, thereby preventing further operation of the cup. From the foregoing description, it will be readily understood that the pressure of the lubricant, in combination with the spring 10, controls the operation of the slide valve 8 so that the rate of flow of lubricant through the passage 14 is the same throughout the entire stroke of the piston.

The vent 16 is provided to permit any lubricant, which might leak by the slide, to pass out of the cup and not interfere with the operation of the valve.

While I have shown and described a preferred embodiment of my invention, it will be understood that changes involving omission, alteration, substitution and reversal of parts, and even changes in the mode of operation, may be made without departing from the scope of my invention which is best defined in the following claim:

30 A lubricant cup comprising a reservoir having a cap and an outlet passage, a piston slidable in said reservoir, a conical helical spring tensioned between said cap and piston, a hollow piston rod having a quick detachable fitting on its exterior end, a valve chamber in communication with the outlet passage of the reservoir, a slide valve located in said chamber, said reservoir having a port in communication with the valve chamber at 35 one side of said valve to permit lubricant to act on the valve in one direction, the bore of the valve chamber being of restricted diameter adjacent one end thereof to provide a shoulder at its junction with the enlarged bore, said shoulder acting as a stop for the valve in one direction of its movement to prevent total closure of the reservoir outlet, a spring for moving said valve in a direction away from said shoulder, and an adjustable 40 stop in the other end of said valve chamber to limit the extent of movement of the valve under the influence of said spring.

In testimony whereof, I have signed my name to this specification.

PERLEY H. FULLER.
